Attorneys

UNITED STATES PATENT OFFICE.

JOHN W. FARLEY, OF CLEVELAND, OHIO.

RADIATOR HANGER.

Application filed March 21, 1921. Serial No. 454,033.

To all whom it may concern:

Be it known that I, JOHN W. FARLEY, a citizen of the United States, residing at Cleveland, in the county of Cuyahoga and State of Ohio, have invented certain new and useful Improvements in Radiator Hangers; and I do declare the following to be a full, clear, and exact description of the invention, such as will enable others skilled 5 in the art to which it appertains to make and use the same.

This invention relates to an improved device for securing a radiator of the wall type and one object of the invention is to provide 15 a radiator securing device or hanger so constructed that it may obtain a firm grip upon the radiator and thus effectively support the same and further to so construct the device that it may be easily adjusted so that the 20 portion thereof which extends beneath the radiator may be moved upwardly into proper engagement with the same.

Another object of the invention is to so construct this radiator hanger that ready 25 access may be had to the rod which carries the radiator engaging element and is vertically adjusted when it is desired to bring the lower radiator engaging element into proper engagement with the radiator.

Another object of the invention is to so 30 construct the device that it will be positioned between the radiator and the wall where it will be concealed by the radiator.

Another object of the invention is to so 35 construct the radiator hanger, that the bracket portions thereof may be supported from the wall either by means of bolts embedded in the wall or by means of supports carried by the wall and engaged by hooks 40 at the upper and lower ends of the brackets.

Another object of the invention is to provide 45 a device which may be easily and quickly put in place or released and which will be very effective when in operation and not liable to slip out of engagement with the radiator.

This invention is illustrated in the accompanying drawings, wherein:

Figure 1 is a view showing the improved 50 radiator hanger principally in vertical section, certain elements thereof being shown in elevation and a radiator supported by the device being indicated by dotted lines.

Figure 2 is a perspective view of the 55 brackets shown in section in Fig. 1.

Figure 3 is a perspective view of the radiator engaging element which engages the lower end of the radiator.

Figure 4 is a view in side elevation showing a modified form of radiator engaging 60 elements.

Figure 5 is a perspective view of the upper radiator engaging element shown in Fig. 4.

Figure 6 is a perspective view of the nut 65 locking device for engaging the nut at the upper end of the rod shown in Fig. 1.

Figure 7 is a perspective view of a guide for the shank portion of the lower radiator engaging element shown in Fig. 4. 70

Figure 8 is a perspective view showing the radiator engaging means of Fig. 4 applied to a bracket having its hooked upper and lower end portions connected with wall 75 engaging supports.

Figure 9 is a fragmentary perspective view of the upper end portion of the bracket with the bracket engaging a modified form of wall engaging support.

This improved radiator hanger is provided with a bracket 1 which is constructed as shown in Figs. 2 and 8. Referring to Fig. 2 where a separate view of the bracket is shown, it will be seen that this bracket may be formed from a strip of heavy metal bent 80 to provide vertically disposed section 2 and horizontally disposed sections or arms 3 and 4 at the upper and lower ends of the bracket. The arm 3 has its end portion bent to provide an outwardly extending hook 5 and 85 the arm 4 has its end portion bent to provide an upwardly extending hook 6 the bill of which extends downwardly below the arm 4 as shown at 7 providing an extended end in which a fastener receiving opening 90 95 may be formed. The hook 5 is also provided with a fastener receiving opening 9 and the arms 3 and 4 are provided with openings 10 and 11 for a purpose to be hereinafter brought out. A slot 12 is formed 100 longitudinally in the body portion or vertically disposed section of the bracket near the upper end thereof. From the above, it will be seen that when this device is in use, supporting bolts 13 may be passed 105 through the openings 8 and 9 and securing nuts put in place or the hooks 5 and 6 may engage brackets carried by the wall. These brackets may be of the type indicated by the numeral 14 in Fig. 8 which would be 110

connected with the wall by suitable bolts, or they could be of the type indicated by the numeral 15 in Fig. 9, in which case the support would be embedded in the wall similar to the manner in which the bolts 13 are embedded in the wall. It should be noted that the brackets 14 and 15 are elongated so that they extend upon opposite sides of the hooks 5 and 6 thus permitting the bracket 1 to be moved along these brackets and thus adjusted to bring the radiator-engaging elements into proper position for extending between sections of a radiator.

In the form shown in Fig. 1, there has been provided a supporting rod 16 which extends upwardly through the openings 11 and 10 and has its upper end portion threaded and carrying a securing nut 17 which rests upon the upper face of the arm 3 and is engaged by a locking clip 18 so that this nut will be prevented from turning when the supporting rod is rotated. A head 19 is provided at the lower end of this rod for engagement by a suitable wrench or other tool when it is desired to rotate or turn the rod and thus cause the rod to move through the nut 17 for vertical adjustment. A second nut 20 is mounted upon this rod 16 at the lower end of the threaded portion and provides an abutment for engagement by the head 21 of the lower radiator engaging element shown in Fig. 3. This radiator engaging element is formed from a strip of heavy metal and has one end portion bent to provide a radiator engaging hook 22 which extends outwardly from the shank 23 of the radiator engaging element. Notches are formed in the sides of this strip adjacent the second end portion thus providing a reduced neck 24 which will be positioned in the slot 12 when the head 21 is passed through the slot and the supporting element then swung downwardly to extend in the position shown in Fig. 1. An opening 25 is formed in the head 21 through which the threaded portion of the rod 16 will pass. An eye-bolt 26 is mounted upon this rod 16 above the head 21 and extends outwardly between the sections of the radiator. A wedge 27 is slidably mounted upon the threaded end portion of this eye-bolt 26 and is engaged by a securing nut 28 so that when the nut 28 is tightened, the wedge may be moved inwardly into tight binding engagement with the upper portion of the radiator. It will thus be seen that this eye-bolt 26, wedge 27 and securing nut 28 provide an upper radiator engaging element supported upon the threaded upper end portion of the rod 16 above the head 25 of the lower radiator engaging element.

When this device is in use, it will be assembled as shown with the hook of the lower radiator engaging element extending beneath the radiator and the rod 26 of the

upper radiator engaging element extending between the sections of the radiator. As previously explained, the brackets carrying the radiator-engaging elements may be moved along the wall carried brackets so that the radiator-engaging elements may be brought into the proper position to extend between the sections of the radiator. The wedge 27 will be put in place and the nut 28 screwed upon the threaded outer end of this rod. The rod 16 will then be turned so that it will be caused to move upwardly and as it moves upwardly engagement of the head 21 by the nut 20 will cause the lower radiator engaging element to move upwardly into tight engagement with the radiator. The nut 28 can then be tightened and the wedge 27 will be drawn into tight binding engagement with the upper portion of the radiator. It will thus be seen that the radiator will be securely gripped and held in the proper position. It will be further noted that the rod 16 can be readily adjusted or released when desired by simply turning the head 19 and rotating the rod. The shank portion of the lower radiator engaging element will be engaged by a sleeve 29 mounted upon the vertically disposed portion of the bracket 1. This sleeve 29 will have the construction disclosed in Fig. 7.

In the construction shown in Figs. 4, 5 and 8, the bracket will be of the same construction disclosed in Figs. 1 and 2 but the radiator engaging elements have a different construction. The lower radiator engaging element is formed from a length of heavy rod metal having one end portion bent to provide hooks 30 which correspond to the hook 22. The rod is then bent to form a shank portion 31 and arm 32 which extend through the slot 12 and is then bent to provide an upwardly extending stem 33 which extends upwardly through the opening 10 of the upper arm 3. This stem 33 is threaded and carries nuts 34 and 35 between which the upper radiator engaging element or hook 36 is mounted. By adjustment of the nuts 34 and 35, the lower radiator engaging element may be drawn upwardly or lowered and the upper radiator engaging element or hook 36 secured in place. An eye 29 may be provided for the shank portion 31 to pass through or a guide such as shown in Fig. 8 and designated by the numeral 37 may be provided. When the guide 29 is in use, the shank portion 31 will be positioned in the off-set which extends from the outer portion of this guide and movement of this shank transversely of the vertical portion of the bracket 1 will be prevented. It will thus be seen that this device operates somewhat similar to the form shown in Fig. 1 but is provided with a somewhat different construction and further is operated in a slightly different manner. In both construc-

tions, however there is provided a wall engaging bracket and upper and lower radiator engaging elements which may be brought into proper position for engaging 5 a radiator and secured in this adjusted position.

I claim:

1. A bracket of the character described having a vertically disposed section and upper and lower rearwardly extending arms, the end portions of the arms being bent upwardly and then rearwardly and downwardly to form hook elements for engaging elongated transversely extending wall- 10 carried supports and slidably mount the bracket upon the supports whereby the bracket may be adjusted transversely.
2. A radiator hanger comprising a wall-engaging bracket having a vertically dis- 20 posed section and arms extending rearwardly from the upper and lower ends of said section, the vertically disposed section being provided with a longitudinally ex- tending slot in its upper end portion, an

engaging element for engaging the lower 25 portion of a radiator having a shank portion extending longitudinally of the vertically disposed section of the bracket against the outer face thereof and bent to provide a portion extending through the slot and 30 terminating in a stem portion extending upwardly through the upper arm, a fastener upon the upper end portion of said stem, a guide slidably mounted upon the vertically disposed portion of the bracket and 35 having its outer portion provided with an offset portion forming a pocket receiving the shank portion of the radiator-engaging element to hold the same against movement transversely of the bracket, and an engag- 40 ing element for engaging the upper portion of a radiator mounted upon the upwardly extending stem portion of the first mentioned radiator-engaging element.

In testimony whereof I have hereunto set 45 my hand.

JOHN W. FARLEY.
